SILAS McCCLURE, OF MINNEAPOLIS, MINNESOTA.

THERMOSTATIC MECHANISM.

Application filed January 24, 1923. Serial No. 614,640.

To all whom it may concern:

Be it known that I, SILAS McCCLURE, a citizen of the United States, resident of Minneapolis, in the county of Hennepin and State of Minnesota, have invented certain new and useful Improvements in Thermostatic Mechanisms, of which the following is a specification.

This invention relates to new and useful improvements in thermostatic mechanisms adapted to be positioned within spaces subject to temperature fluctuations and to be responsive thereto in order to control or effect movements of other devices such as valves, dampers, switches, etc. It is old in this art to employ a tube fixedly secured at one end and containing an elongated rod having a different coefficient of expansion. One end of the rod is usually affixed to one end of the tube while the other rod end freely projects from the tube and is connected to a lever, lever system, or other transmission device to carry the power produced by the expansion differential to the place of control. Two striking disadvantages of the rigid thermostatic elements reside in their manifest limitations as to location and effective length. The element must obviously be placed within the compartment of which the temperature is to be regulated and hence the element is usually remote from the valve, switch or other control to be thermostatically operated. This necessitates the employment of various apparatus for the transmission of the force of the expanded or contracted element with consequent liability to derangement, multiplicity of parts, disfigurement of the controlled object and expense. The effective length of the usual rigid thermostatic element is subject to the dimensional limitations of the compartment. The result is relatively slight movement of the thermostatic element for given temperature changes in turn entailing the necessity for multiplying levers or systems of levers to attain the desired range of valve movement or throw of a switch. In the art of thermostatically controlling the oven temperature of gas ranges, these disadvantages are particularly striking. The gas valve must be adjacent the burner to effect most accurate control. The rigid thermostatic element must be located in the oven which is remote from the burner manifold. Hence, various transmission ap-

pliances, multiplying levers, etc., are externally employed at present to permit the small thermostatic movement to act adequately upon the gas valve. These appliances are unwieldy, cumbersome, and disfiguring. 60 They are expensive to manufacture and require a large amount of space in crating and shipment as well as after installation. These many additional parts are themselves subject to unequal expansion and contraction 65 to the detriment of accuracy. If the gas valve be positioned adjacent the rigid thermostat, then special piping is required to conduct the gas supply to the valve and to conduct the controlled flow to the oven 70 burner.

It is well-known that the efficiency and accuracy of control suffers from increase of distance between the control valve and point of use. In short, these present devices may 75 not be positioned with relation to convenience and efficiency but their locations are governed by the limitations of the rigid thermostatic element.

This novel thermostatic element is one 80 adapted to function when in a curved or irregular form. It broadly includes a tube and flexible member of different coefficients of expansion and will efficiently and accurately function when the tube assumes a path 85 other than straight. This novel type of element may extend from the oven to a valve adjacent an oven burner and its effective length is not confined to that of a single straight line in the oven but may assume 90 a grid-like, convoluted or tortuous path in the oven. Hence, not only may the thermostatically derived force be directly applied at the most convenient and efficient point, but the amount of desired movement may be 95 directly obtained.

The object therefore of this invention is to provide an improved thermostatic mechanism.

Other objects of the invention will more 100 fully appear from the following description and the accompanying drawings and will be pointed out in the annexed claims.

In the drawings, there has been disclosed 105 a structure designed to carry out the objects of the invention but it is to be understood that the invention is not confined to the exact features shown as various changes may be made within the scope of the claims which follow.

In the drawings:

Figure 1 is a view in front elevation of the oven and adjacent portions of a common form of gas range with part of the oven broken away to show the novel thermostatic mechanism;

Figure 2 is a vertical sectional view on the line 2—2 of Figure 1;

Figure 3 is a cross-sectional view of a center-burner oven to show a different arrangement of the novel mechanism;

Figure 4 is a cross-sectional view of a valve with the novel thermostatic element operatively connected;

Figure 5 is an enlarged detail view of a portion of the valve mechanism shown in Figure 4;

Figure 6 is an enlarged view in side elevation of the valve end of the novel element with parts broken away to show the bearing rings and lubricant;

Figure 7 is a view similar to that of Figure 6 but showing the oven end of the novel element; and

Figure 8 is a longitudinally sectional view of the tube to show the coil form of bearing member both in section and in side elevation.

The invention broadly includes a tubular member and a flexible member having different coefficients of expansion for the same temperature changes. The flexible member is adapted to extend longitudinally within the tubular member preferably

with a running guiding bearing therein and to be fixed at one end thereto while the other end freely projects beyond the tubular member for working connection with the movable part of a valve, switch or other control-

ling means. There is here shown an elongated tube 11 adapted to bear a wire 12. The tube may be of brass which has a relatively high coefficient of expansion while the wire may be of steel having a relatively low one.

However, an alloy of steel having a relatively low coefficient of expansion coupled with non-corrosive attributes may be employed. The relation of the inside diameter of the tube to the outside diameter of the wire is such that the wire, is, at least, provided with a running guiding fit. The wire 12 is flexible in order that the tube may be arcuately curved when installed, both to assure presentation of sufficient length within an oven and to permit the wire to extend to, and directly contact with, the parts to be actuated.

As is shown, in detail in Figures 5 to 8, inclusive, it is advantageous to insert a bearing member within the tube by which the wire is borne. Two practical forms of such bearing member are suggested in the drawings. One consists of a series of rings and the other of a coil. The wire 12 extends through the rings or coil convolutions with

a running guiding fit, and out of contact with the inside face of the tube wall. In Figures 5, 6, and 7, the ring type of bearing member is shown as comprising a plurality of metallic rings 13. Each ring is preferably circular in cross-section to avoid engagement of any angled ring edges when the tube is bent into the desired shape and placed in operation. These rings may be conveniently inserted in the tube to assume the substantially abutting relation shown in the drawings and the working wire 12 may concentrically project therethrough. The relative dimensions of the wire and rings are preferably such as to afford a running guiding fit to the wire and yet not too loose so as to permit buckling of the wire. The coil form of bearing member is shown in Figure 8 wherein there is disclosed a coil 14 of suitably dimensioned flexible wire positioned within the tube 11. The working wire 12 extends through the convolutions of this coil and likewise is thereby provided with a running guiding fit out of contact with the wall of the tube 11 to avoid frictional resistance to the desired relative movement between tube and working wire.

A lubricating medium may be placed within the tube 11 as is suggested in Figures 5, 7 and 8. Such lubricant 15 may be provided by particles of graphite or mica or a mixture of both. The purpose of the lubricant is to minimize any frictional resistance to relative movement of the working wire 12 and the rings or coil, or between the rings themselves or the coil convolutions, or between either and the inside face of the tube wall.

The working wire is fixedly secured to the tube at one end and freely projects therefrom at its other end. A means of fixedly securing one end of the wire 12 to the tube is shown in Figure 7 wherein a terminal portion of the wire 12 is upset to form an enlarged head 16 to effect a driving fit with the tube interior. The outer portion of this head is tapered in order to provide space to receive brazing metal 17 by means of which a fixed gas-tight connection of wire and tube is assured, at this oven end. Thus, any differential of expansion or contraction must be communicated to the free end of the working wire which terminally projects from the other end of the tube and the resultant relative movement may be employed to actuate the movable part of a controlling device.

A specific adaptation of this novel thermostatic mechanism is illustrated in the accompanying drawings wherein the wire-containing tube 11 is shown as introduced within the oven portion of common forms of gas ranges. In Figures 1 and 2 there are shown portions of a gas range such as an oven 18

with grid racks 19, dead air jackets 21, circulating flues 23, gas manifold 24, cooking burner mixers and valves 25, oven burner 26 and its mixer 27, all in conformity with modern gas range practice.

By the employment of this novel thermostatic mechanism, the valve for the oven burner may be placed in its most efficient position, i. e., adjacent the oven burner mixer 27. Not only may the valve be efficiently so placed but the actuating thermo-element may be extended from its oven position directly to the movable part of the valve. The efficiency, convenience and advantages of such arrangement are indicated in Figures 1 to 3 inclusive. The effective length of the thermostatic element is not limited by any straight line dimension of the oven but may be curved and loosely suspended from a bracket 29 borne by one of the jackets 21. This novel element is also equally useful with the type of center burner shown in Figure 3 wherein the valve is shown at the oven burner mixer 27 while the element curves to one side of the oven and is similarly carried by a bracket 29. Obviously, the element will function equally well when shaped into irregular forms or paths other than the substantially circular forms suggested in the drawings.

While other forms of gas valves may thus be thermostatically controlled, there is shown in Figure 4, a specific form of novel valve which forms the subject-matter of another patent application of which the inventor hereof is one of the joint inventors. Generally, this novel valve includes a housing 31 substantially cylindrical in shape and closed at its ends by a front plate 32 and rear plate 33. The housing has an integral casting 34 having an integral recessed head 35 to receive, in threaded engagement, the end of the gas manifold 24. The casting 34 is centrally counterbored to form a gas passage from the head to the mixer 27 through the nipple of the casting 34. A manually operable valve 37 is interposed in this central gas passage so that it may be manually turned to permit gas to flow directly from the inlet portion 38 thereof, through the valve port 39, to the outlet portion 41 and thence to the burner mixer 27. When so turned, the gas supply can not be thermostatically controlled. This manual valve also has a port 42 which is shown in Figure 4 as presented to the inlet portion 38 to permit gas to flow to the inlet conduit 43 on one side of the integral web 44 which divides the valve housing into an inlet chamber 45 and outlet chamber 46. An outlet conduit 47 leads from the chamber 46 to the outlet portion 41 of the gas passage to the mixer. A by-pass 48, suitably constricted, is provided to supply sufficient gas to the mixer 27 to function as a pilot between the forward face of which and the

for the burner during periods of thermostatic control.

The valve end of the tube 11 is preferably outwardly flared, as shown in Figure 6, and is tightly engaged by a recessed nut 49 adapted to be received in threaded engagement within a boss 51 of the rear plate 33 so that this end of the tube may be held in rigid fixed position. The wire 12 freely projects from this valve end of the tube 11 and is adapted to control the operative positions of a valve within the housing 31.

Broadly, this novel valve mechanism includes a sleeve 52 having an intermediate peripheral conoidal valve 53 adapted to contact with the front edge of the central aperture of the web 44. This valved aperture forms the passage for gas between the inlet chamber 45 and the outlet chamber 46. A regulating shaft 54 is received in adjustable threaded engagement and longitudinally extends through the sleeve 52. The rear end of this shaft is enlarged to provide a head having a running guiding fit within the recessed boss 55 forwardly extending from the rear plate 33. This head is provided with a central terminal recess to receive the end portion of the wire 12.

Means are provided tensionably to hold the valve-carrying shaft against the end of the wire so that the wire movements may be communicated directly to the shaft. As the sleeve is carried in threaded engagement on the shaft, the sleeve is normally held against rotation so that rotation of the shaft may vary the relative position of the sleeve on the shaft to the end that the valve may be manually set to admit the passage of a supply of gas sufficient to bring the oven temperature to, and maintain it at, a predetermined degree.

The forward end of the shaft is formed with a transverse slot to receive a tongue 56 terminally projecting within the casing 110 from a plug 57. This plug has a tapered body portion, outwardly diminishing and received for rotative movement within a complementarily shaped aperture in an externally tapered block 58 likewise mounted 115 in a tapered aperture in the front plate 32. The forward end of the sleeve is provided with opposed tongues 59 received in diametrically alined slots in the annular wall 61 formed by counterboring the rear end of the block. The block 58 is provided with an outwardly terminal stem of irregular cross-section upon which is mounted the calibrating disk 62 which is normally held against rotation by the screw 63 mounted in 120 the front plate with the screw-head overhanging a peripheral portion of the disk. The wall 61 of the block is peripherally threaded for engagement by the ring-nut 64

rear face of the plate 32 is positioned the coiled compression spring 65 which reacts rearwardly to pull the block in its tapered seat. A compression spring 66 is likewise coiled about the sleeve between the projecting shoulder formed by the valve 53 and a washer held by the nut 64. This spring 66 exerts a rearward thrust upon the sleeve to hold the shaft against the wire 12.

- 10 The forward end of the plug 57 is provided with a reduced portion forming a hub 67 having a threaded end portion 69 to receive a nut 68. A compression spring 70 is coiled about the hub and held between 15 the base of a recess in the block 58 and the nut whereby the plug is tensionably thrust forwardly to assure gas-tight seating in its tapered aperture in the block 58. A dial wheel 71 is held to the plug hub by means of 20 the screw 72. The dial wheel, which is graduated to cooperate with a suitable mark on the housing to indicate corresponding oven temperature conditions, provides a convenient means for the manual adjustment of 25 the regulating shaft with relation to the valve-carrying sleeve. The calibrating disk which normally holds the sleeve in non-rotatable position, may be rotatably adjusted to change a normal operative position of 30 the sleeve with relation to the shaft so that the mechanism may be corrected or calibrated for any inaccuracies in installation or maintenance. As this novel valve mechanism forms the subject-matter of another application, it need not be described 35 in greater detail as this novel thermostatic element is capable of use with various other types of valve mechanisms.
- 40 In the operation of this mechanism and thermostatic element, the dial wheel may be set, as is usual, to indicate the predetermined oven temperature. The resulting shaft movement adjusts the position of the valve-carrying sleeve to permit a definite 45 rate of flow of gas through the valve housing to the oven burner. As the oven temperature approaches the predetermined degree, the tube and wire are expanded, the 50 rate of expansion of the brass tube being greater than that of the alloy steel wire so that the free end of the wire is drawn toward the tube and from the shaft end. The shaft tensionably follows the wire end with the result that the valve is carried toward 55 its seat to cut down the gaseous flow. Conversely, when the tube and wire are cooled 60 they contract, the rate of contraction of the tube being greater than that of the wire. Hence, as the tube and wire are fixed together at their oven ends and the wire freely projects from the tube at its fixed valve end, the free end of the wire is pushed farther from the tube and moves the shaft forwardly to carry the valve to a more open 65 position.

Having thus described my invention what I claim as new and desire to secure by Letters Patent, is:

1. In a thermostatic mechanism, the combination of a tubular member adapted to be shaped into a curved or irregular form, a flexible element having a different coefficient of expansion extending longitudinally of and having a running guiding fit within said member, one end of the member and of the element being secured together so that the other portions thereof may have relative movement upon temperature changes, whereby the mechanism may thermostatically function when assuming a curvilinear or irregular path.

2. In a thermostatic mechanism, the combination of a tubular member adapted to be shaped into a curved or irregular form, a flexible element having a different coefficient of expansion extending longitudinally within said member, one end of said member and element being secured together so that the other portions thereof may have relative movement upon temperature changes, and bearing means within said member to provide a running guiding fit for the element, whereby the mechanism may thermostatically function when assuming a curvilinear or irregular path.

3. In a thermostatic mechanism, the combination of a tubular member adapted to be shaped into a curved or irregular form, a flexible element having a different coefficient of expansion extending longitudinally within said member, one end of said member and element being secured together so that the other portions thereof may have relative movement upon temperature changes, and bearing means surrounding said element within said member to provide a running guiding bearing for the element, whereby the mechanism may thermostatically function when assuming a curvilinear or irregular path.

4. In a thermostatic mechanism, the combination of a tubular member adapted to be shaped into a curved or irregular form, a flexible element having a different coefficient of expansion extending longitudinally within said member, one end of said member and element being secured together so that the other portions thereof may have relative movement upon temperature changes, and a plurality of loops extending around said element within said member to provide running guiding bearings for the element, whereby the mechanism may thermostatically function when assuming a curvilinear or irregular path.

5. In a thermostatic mechanism, the combination of a tubular member adapted to be shaped into a curved or irregular form, a flexible element having a different coefficient of expansion extending longitudinally with-

in said member, one end of said member and element being secured together so that the other portions thereof may have relative movement upon temperature changes, and an 5 instrumentality coiled about said element within said member to provide running guiding bearings for said element whereby the mechanism may thermostatically function when assuming a curvilinear or irregular 10 path.

6. In a thermostatic mechanism, the combination of a tubular member adapted to be shaped into a curved or irregular form, a flexible element having a different coefficient 15 of expansion extending longitudinally within and having a running guiding fit within said member, one end of the member and element being secured together so that the other portions thereof may have relative 20 movement upon temperature changes, and lubricating means for said element within said member, whereby the mechanism may

thermostatically function when assuming a curvilinear or irregular path.

7. In a thermostatic mechanism, the combination of a tubular member adapted to be shaped into a curved or irregular form, a flexible element having a different coefficient of expansion extending longitudinally within 25 said member, one end of the member and element being secured together so that the other portions thereof may have relative movement upon temperature changes, bearing means for said element within said member to provide a running guiding bearing 30 for the element, and lubricating means for the element-bearing means, whereby the mechanism may thermostatically function when assuming a curvilinear or irregular 35 path.

In witness whereof, I have hereunto set my hand this twentieth day of January 1923.

SILAS McCLURE.
